UNITED STATES PATENT OFFICE

JOHN E. SCOTT, OF DANVILLE, ILLINOIS, ASSIGNOR TO ALLITH-PROUTY COMPANY, OF DANVILLE, ILLINOIS, A CORPORATION OF DELAWARE

LOCK FOR DOOR ROLLERS

Application filed January 20, 1930. Serial No. 421,914.

This invention relates to a lock for door rollers and particularly for one with heavy rollers used to support large doors, partitions, and the like.

Recently there have come into use very large doors for hangars, aerodromes and similar structures, which doors are supported on rollers of considerable weight and strength for the purpose of moving the doors easily into opened and closed positions. These doors are very heavy, necessitating therefore some means for locking the rollers against accidental movement.

Hangar and aerodrome doors and the like are arranged so that the rollers supporting the doors travel on rails for easy movement of the doors, and consequently it requires but slight effort to roll these doors on the tracks.

It is an object of the present invention to provide means for locking hangar door supporting rollers against movement.

Another object of the invention is to provide a friction lock for door roller which is normally in locking position and which may readily be unlocked as desired.

A further object of the invention is to provide a cam lock for door rollers which is maintained normally in locking position and which may be readily unlocked to allow movement of the rollers.

Another and further object of the invention is to provide locking means for hangar door rollers wherein friction cams are provided for engagement with rollers or wheels and which cams are maintained in locking position normally and moved out of locking position by suitable mechanism. The cams are so designed that when in locking position any tendency of the roller to move will increase the frictional engagement with the cams.

A still further object of the invention is to provide locking means for hangar door rollers or wheels wherein pivoted cams are utilized and which cams are maintained in frictional locking engagement with the rollers or wheels by resilient means and which are moved out of braking or locking position by a key or similar structure moving the cams

in opposition to the effect of the resilient means.

According to the invention the lock or brake contemplates the provision of a cam arranged to engage a portion of the roller or wheel and lock the roller or wheel against rotation in either direction, together with means for freeing the cam from engagement with the wheel as desired.

The above other and further objects of the invention will be apparent from the following description, accompanying drawings and appended claims.

An embodiment of the present invention is illustrated in the accompanying drawings and the views thereof as follows.

Figure 1 is a fragmental inside elevational view of a portion of a door provided with a roller or wheel construction embodying the present invention.

Figure 2 is an enlarged fragmental sectional view showing the illustrated form of cams in frictional locking or braking engagement with a flange of a roller or wheel.

Figure 3 is a view similar to Figure 2 showing the cams moved out of frictional braking or locking engagement with roller or wheel.

Figure 4 is a vertical sectional view taken substantially in the plane of line IV-IV of Figure 1 showing certain parts in section and other parts in full lines.

Figure 5 is an enlarged fragmental sectional view taken substantially on line V-V of Figure 1.

Figure 6 is a sectional view taken substantially on line VI-VI of Figure 1 looking in the direction indicated by the arrows.

Figure 7 is an elevation of removable handle with stem in section.

Figure 8 is a view similar to Figure 2 showing the cams in full lines and with the key engaging faces of the cams as straight. The parts are shown in locking position.

Figure 9 shows the parts of Figure 8 in unlocked position.

Figure 10 is a view of a modified handle for the operating key with lugs on the wheel casting for limiting movement of the handle in either direction.

A fragmental portion of the lower corner

of a hangar door is illustrated in Figure 1 and as there illustrated includes a tube 1 which services as one side member of the door and a tube 2 spaced from tube 1. There are a plurality of said tubes or frame members in the door when same is made of sheet metal or the like.

A roller frame A has side members 3 and 4 which are attached to the inner faces of the tubes or frame members 1 and 2 by means of bolts 5 or similar attaching means. The upper end of the frame A is formed to provide a cylindrical recess 6 while the lower portion is formed to provide an enlarged cylindrical recess 7, the recesses 6 and 7 being in axial alignment. The frame A is cut away to provide a central opening 8.

The frame A at the lower end of the cylindrical portion 6 is enlarged to provide a counter bore 9 in which is seated anti-friction members 10 surrounding a stub shaft 11 which is vertically supported in the frame A. The shaft 11 passes through the anti-friction members 10 and immediately below the same is provided with a polygonal portion 12 whereby a wrench or similar tool may be applied. The shaft below the polygonal portion 12 is screw threaded at 13 for entering the threaded interior of a cylindrical extension 14 which passes through the cylindrical opening 7 in the frame A and integrally formed with which is a yoke 15 having downwardly extending side members 16 and 17 for supporting a roller or wheel B.

The side 17 of the yoke has an opening 18 through the same while the side 16 has a threaded opening 19 in axial alignment with the opening 18 in the other side of the yoke.

A shaft 20 having a threaded end 21 and a head 22 passes through the opening 18 in the yoke member 17 and is threaded into the opening 19 in the yoke member 16 for supporting the roller or wheel B.

Anti-friction members 23 and 24 are interposed about the shaft 20 and engage against the hub of the wheel B for supporting same on the shaft 20.

The head 22 is provided with a plurality of indentations 25 for cooperation with a set screw 26 entering the member 17 of the yoke for locking the shaft 20 in position in the yoke. The shaft 20 is turned to tighten the wheel B in any desirable manner, then the set screw 26 is inserted in the member 17 of the yoke through one of the indentations 25 of the head 22, thus locking the shaft against movement in the yoke.

The wheel or roller B secured in the manner above described has rotative or swivel movement in the bracket A as to rotate when the door passes over a curved section of track.

The provision of the screw portion 13 of the shaft 11 enables vertical adjustment of the roller B with respect to the bracket A to properly hang the doors and also to accom-

modate the rollers to position the doors the desired distance above the track C.

The fact that the roller B is pivoted in its bracket A necessitates a cover plate for the roller opening to prevent admission of dirt, ice, sleet, snow and the like. The illustrated form of cover for the roller contemplates a plate 27 hinged at 28 to the tube or post 2 and overlying the roller B. The plate is shown in the illustrated form of the invention as being on the outside of the door as shown in Figure 6. The plate 27 of Figure 1 is the inside of the plate.

A spring 29 is fastened at one end to an eye 30 attached to the post or tube 2 and at the other end is secured to an eye 31 fastened to the plate 27 and normally holds the plate in closed position with its free or outer edge 32 against the outer post or tube 1 as observed in Figure 6.

Figure 6 shows the wheel B pivoted to an extent to move the plate 27 away from the post or tube 1 and showing the position of the parts in this relation.

The sides 16 and 17 of the yoke are extended at 33 and 34 to bear against the inside of the plate 27 and urge the same outwardly whenever the wheel B is swiveled in the bracket A as it passes along the track C.

Another plate could if desired be placed over the inside of the wheel or roller B in which event another spring similar to spring 29 would be secured to the other plate for keeping the same closed in the same manner as described in respect to plate 27.

The roller frame A is covered on each side by side plates 35 and 36 which plates terminate short of the yoke 15.

Plates 35 and 36 are secured in position on the door by means of screws 37 engaging portions of the frame A.

The roller or wheel B has flanges 38 and 39 for guiding the roller or wheel on track C. The roller is formed with an internal flange 40 and a hub 41.

A collar 42 surrounds the hub 41 and is freely movable on the same. Ears 43 and 44 are formed integrally with the collar 42 in axially spaced relation and extends radially from the collar.

Cams 45 and 46 are pivotally supported on posts 47 and 48 respectively carried in the ears 43 and 44 between the shaft 20 and the flange 40. The cams are opposed in position so that one cam will effectively oppose rolling movement of the roller when force is applied to the door to move same in one direction when locked and the other cam opposing effect to move the door in the opposite direction. The faces of the cams are curved more sharply than the flange 40, hence the high points of the cam faces touch the flange 40 and increase or tend to increase contact when an attempt is made to move the door in either direction. Each of the cams 45 and 46 has

- an arcuate engaging surface 49 described on a shorter radius than the radius of the annular flange 40 so that when in braking or locking position and an effort is made to move the supported door in either direction, one of the cams will be forced into tight engagement with the flange 40, or other part of the wheel, and effectively lock the roller against movement.
- 10 The collar 42 is provided on opposite sides with bosses 50—51 for supporting springs 52—53. The other ends of the springs engage bosses 54 and 55 respectively on the cams 45 and 46 to prevent disengagement of the springs 52 and 53. Normally the springs 52 and 53 act against the cams 45 and 46 to force the cam surfaces 49 against the inner annular flange 40 for braking or locking roller B against rotation with respect to the collar 42.
- 15 An actuator 56 constituting in the present instance a cylindrical end 57 for entering a similarly shaped aperture in the ear 44 and a stem 58 with oppositely extending cams 59 and 60 is secured in a bushing 61 which is threaded at 62 in the member 17 of the yoke. Set screw 63 is used to lock the bushing 61 in position in the yoke 17 when the actuator 56 is installed.
- 20 A bushing 64 surrounds the end 57 of the actuator.
- The actuator 56 is arranged to extend between adjacent ends of the cams 45 and 46 while the cam portions 59 and 60 thereof are arranged to move the cams 45 and 46 out of braking or locking position with the flange 40 of the roller or wheel B.
- 25 The faces 65 and 66 of the cams 45 and 46 respectively which are engaged by the cam ends 59 and 60 of the actuator are shaped and arranged so as to allow easy operation of the cams by the actuator 56.
- The actuator 56 is in locking position when in the position shown in Figures 2 and 8. The wheel or roller is thus potentially locked by reason of the engagement of the cams with the flange 40, the cams being moved into such engagement by the springs. Locking, however, does not occur until a tendency to move the door arises, say for instance, in clockwise direction, whereupon the cam 45 will be carried in lockwise direction by virtue of its contact with the flange 40 creating increasing pressure thereagainst to an extent as to prevent rolling movement of the wheel. Thus the wheel or roller is locked. The springs 52 and 53 hold the cams 45 and 46 against the flange 40.
- 30 The action of the cams, in the manner described, is a locking or gripping action and is utilized after the door comes to rest to lock the door against intentional unauthorized movement. The weight of the door is such as to obviate the possibility of sliding the rollers or wheels when locked.
- The faces 65 and 66 of the cams extend
- high enough so as to allow the ends of the actuator to strike same in order to move the cams into unlocked position.
- 35 The outer end of the stem 58 is provided with a flattened surface 67.
- A handle 68 is provided with an enlargement 69 having a circular opening 70 therein for fitting over the end of the stem 58. Enlargement 69 has another opening parallel to the handle 68 for the reception of a gib 71 which has a threaded end for engagement by a nut 72 for pulling the gib downwardly to lock the handle onto the end of the stem 58 whereby the actuator 56 may be moved into position to unlock the cams 45 and 46 from engagement with the flange 40 of the roller or wheel B. The position of the handle shown in Figure 1 and of the cam faces 59 and 60 of the actuator 56 in Figure 2 is the position assumed by these parts when the roller or wheel B is locked or braked and the position of the parts in Figure 3 is when the wheel is unlocked or the brake released to allow free rotation of the wheel or roller B.
- 40 Should it be desired, the handle 68 might be eliminated and a temporary handle 73 employed to be applied to the stem 58 of the actuator 56 for unlocking the rollers. The stem 58 would in such event be provided with a polygonal or other end 74 of uneven shape so that an ordinary tool would not fit the same and the handle 73 provided with an opening of like shape to be applied over the end 74 of the stem for turning the actuator 56 into unlocking or brake-releasing position. The handle 73 is removable and is to be applied to the actuator 56 only when it is desired to unlock or release the brake holding the roller B against movement on the rail C.
- 45 The roller or wheel B is shown as provided with an inner annular flange against which the cams 45 and 46 engage for locking or braking the roller against accidental movement. However, the cams could be arranged for frictional engagement with some other part of the roller with equally satisfactory results, and therefore the invention is not to be limited to the flange 40, but includes other equivalent arrangements of the parts.
- 50 The posts 1 and 2 while being illustrated and described as tubular are illustrative only, and any desired door construction having provision for the roller frame and roller could be substituted.
- 55 Figure 8 shows the cams 45 and 46 with actuator engaging faces 65a and 66a as straight instead of otherwise as, for instance, as shown in Figures 2 and 3.
- 60 Figure 10 illustrates a different type of handle 73 which consists of an enlargement 74 having a circular aperture 75 in the same for application over the outer end of the stem 58. The handle is straight. The enlarge-

ment receives the gib 71 for securing it to the stem.

Lugs 76 and 77 are cast on the outer plate or side member 17 so that the handle may be moved against either lug when moved to unlocking position. The handle will extend vertically when in locked position.

The invention has been described herein more or less precisely, yet it is understood that the invention is not to be limited thereby, as changes may be made in the arrangement and proportion of parts, and equivalents may be substituted without departing from the spirit and scope of the invention.

15 The invention is claimed as follows:

1. A hangar door roller construction including a roller frame, a roller supported in said frame, said roller having an inner annular flange and a hub, a collar on said hub, a pair of spaced ears extending radially from said collar, cams carried by said ears, springs between said collar and said cams to urge said cams against said flange, and an actuator carried by said ears and extending between said 25 cams for moving said cams away from said flange against the action of the springs when said actuator is turned in either of two directions.

2. A hangar door roller construction including a roller frame, a roller supported in said frame, said roller having an inner annular flange and a hub, a collar free on said hub, said collar having a pair of spaced cams normally engaging said flange, springs for maintaining said cams in engagement with said flange, and an actuator carried by said roller support and lying between said cams for moving said cams out of braking position when said actuator is turned in either 40 of two directions.

3. A hangar door roller construction including a roller having a lateral annular flange and a hub, a member supported on said hub on the same side of the roller as said flange and fixed against rotation, pairs of axially spaced ears extending radially from said member, a cam pivoted between each pair of said ears and having a face engageable with said flange, said cams being oppositely movable, springs between said member and said cams for normally maintaining said cams against said flange in locking engagement, and an actuator supported by said ears for moving said cams away from 55 said flange to release the roller.

4. A hangar door roller construction including a roller having a lateral annular flange and a hub, a member supported on said hub on the same side of the roller as said flange and fixed against rotation, a pair of axially spaced ears extending radially from said member, a pair of oppositely movable cams pivoted between said ears, each cam having a flange engaging face of different 60 radius than the radius of the flange, springs

between said member and said cams for normally maintaining said cams in locking engagement with said flange, and an actuator supported in said ear between said cams for moving said cams away from said flange to 70 release the roller.

5. A hangar door roller construction including a roller having a lateral annular flange and a hub, a member supported on said hub on the same side of the roller as said flange and fixed against rotation, a pair of axially spaced ears extending radially from said member, a pair of oppositely movable cams pivoted between said ears, each cam having a flange engaging face of different 75 radius than the radius of the flange, springs between said member and said cams for normally maintaining said cams in locking engagement with said flange, and an actuator supported in said ear between said cams for moving said cams away from said flange to 80 release the roller, one cam increasing its wedging effect between said member and the flange when effort is made to move the door in one direction and the other cam 85 increasing its wedging effect between said member and said flange when effort is made to move the door in the opposite direction.

In testimony whereof I have hereunto subscribed my name at Danville, Illinois, county 90 of Vermilion.

JOHN E. SCOTT.
